[57] CLAIM

The ornamental design for a disc, as shown and described.

DESCRIPTION

FIG. 1 is a top front perspective view of a disc showing our new design;

FIG. 2 is a bottom rear perspective view thereof;

FIG. 3 is a top plan view thereof;

FIG. 4 is a bottom plan view thereof;

FIG. 5 is a side elevational view thereof, all sides being identical; and,

FIG. 6 is a bottom plan view of a second embodiment of FIG. 1, the difference residing in the bottom surface being flat.
